(57) **CLAIM**

The ornamental design for a display screen or portion thereof with transitional graphical user interface, as shown and described.

DESCRIPTION

FIG. 1 is a front view of a display screen or portion thereof with transitional graphical user interface showing a first image in a sequence showing our new design;

FIG. 2 is a second image thereof;

FIG. 3 is a third image thereof;

FIG. 4 is a fourth image thereof;

FIG. 5 is a fifth image thereof; and,

FIG. 6 is a sixth image thereof.

The appearance of the transitional graphical user interface transitions between the images shown in FIGS. 1 through 6. The process or period in which one image transitions to another forms no part of the claimed design.

The outermost dash-dot broken lines in the drawings illustrate the display screen or portion thereof and form no part of the claimed design. The dotted broken lines in the drawings illustrate portions of the graphical user interface that form no part of the claimed design.

1 Claim, 6 Drawing Sheets

FIG. 1

FIG. 2

Article Title

Text example: In the whole scene, the grayscale of the font has the greatest influence on font recognition and clarity. Due to the size difference of devices, such as TV and watch, the font size will be very different. The display of large font size is ok, but the small font size is difficult to see. And differences in lighting conditions, we know that TV is commonly used indoors at night, weak brightness of word recognition will be weaker, and car machine is used in outdoors scene.
